UNITED STATES PATENT OFFICE.

FRANK THEODORE WILLIAMS, OF MERIDEN, CONNECTICUT, ASSIGNOR TO
THE EDWARD MILLER & COMPANY, OF SAME PLACE.

DESIGN FOR A BICYCLE-LANTERN.

SPECIFICATION forming part of Design No. 27,303, dated July 6, 1897.

Application filed April 20, 1897. Serial No. 633,054. Term of patent 31 years.

To all whom it may concern:

Be it known that I, FRANK THEODORE WILLIAMS, a citizen of the United States, residing at Meriden, New Haven county, Connecticut, have invented and produced a new and original Design for Bicycle-Lanterns, of which the following is a full, clear, and exact description.

My design is illustrated by the accompanying drawings, in which—

Figure 1 is a plan view. Fig. 2 is a side elevation. Fig. 3 is a view of the bottom and under side of the base of the lamp.

The leading features of my design are the general outline and ornamentation, as herein set forth. A is the body portion of the lamp, extending up to the overhanging flange of the top portion B of the lamp. In the body A, near the top B, is a circumferential band of small vertically - arranged ornamental openings C C. The upper surface or top of the lamp is provided with an elevated system of concentric rings G, arranged in terraces.

(See Figs. 1 and 2.) On the front of the body A is a reflector E, having diverging or flaring sides and a horizontal median line. 25

F is a rib around the outer edge of the part E, and G is a second rib of less diameter than the rib F, around said part E, the ribs F and G being separated by a plain band H. 30

I is the base of the lamp, the sides of which are convexed throughout.

J is a rib about midway between the bottom and top of the base I. The bottom K of the base I (seen only in Fig. 3) is concaved. 35 In the space between the body A and base I are narrow outwardly-inclined legs L, projecting part way down the convexed sides of said base I.

What I claim is—

The design for a bicycle-lantern as herein shown and described. 40

FRANK THEODORE WILLIAMS.
